Attorney

UNITED STATES PATENT OFFICE.

J E JOHNSON, OF CHICAGO, ILLINOIS, ASSIGNOR TO THE WAHL COMPANY, OF WILMINGTTON, DELAWARE, A CORPORATION OF DELAWARE.

ERASER-HOLDING DEVICE AND THE LIKE.

Application filed May 23, 1921. Serial No. 471,549.

My invention relates to improvements in eraser holding devices and the like and has for its primary object the two-fold purpose of providing an eraser holding device for 5 mechanical pencils which will securely grip and tightly hold an eraser in any desired position, and secondly, due to its construction and resiliency, will prevent the loss of a cap adapted to cover said eraser holder 10 and eraser, when the frictional engagement between said cap and said eraser holder has been materially weakened due to constant removal of said cap from said eraser holding device for the purpose of using the 15 eraser.

Another object of my invention is to provide an eraser holding device which is simple of construction and economical to manufacture.

Other objects will appear as this description progresses, reference being had to the accompanying drawings, in which

Fig. 1 is a side elevation of the well-known Eversharp pencil, with the inner 25 mechanism, to which is attached the cap, partly unscrewed from the barrel.

Fig. 2 is a longitudinal sectional view of the cap and eraser holding device embodying my invention, and disclosing the attachment of said eraser holding device to the lead magazines.

Fig. 3 is a longitudinal sectional view of said eraser holder on line 3—3 of Fig. 2, and

Fig. 4 is a cross sectional view on line 4—4 35 of Fig. 3.

Referring to the drawings, 10 indicates a pencil barrel tapered as at 11 to form the aperture 12 through which a writing lead is propelled or repelled by means within said 40 barrel 10. Inasmuch as the mechanism of the pencil forms no part of my invention it is not deemed necessary to burden this application with a detailed description of same.

As is most clearly discernible in Fig. 3, the eraser holding device 14 has its upper edge thereof slightly turned in to form the flange 15; said flange is adapted to bite into and hold an eraser inserted in said eraser 45 holding device.

A lip 16 is so formed that the free end of the lip is slightly bent downwardly, causing said end to protrude or extend inwardly to resiliently grip the eraser. Due to the bend-

ing of the lip 16 downwardly, the free end 55 thereof will extend inwardly to bite into an eraser. The outwardly curved portion of the lip 16, as will be observed by reference to Fig. 2, is adapted to seat in a correspondingly curved portion of the cap. The cap 60 may be slipped on or off the eraser holder, as will be readily understood, the lip 16 constituting a means for holding the cap when in position over the end of the holder.

As has been briefly stated heretofore, the 65 ridge or flange 15, acting in conjunction with the free end of the lip 16, tightly grips and holds an eraser in any desired position. thus when an eraser has been worn down to the level of the ridge 15, it can be pulled 70 outwardly any desired distance, care being taken however, to see that the lower end of the eraser is not pulled out beyond the point of contact with the free end of the lip, thus preventing the lip from biting into the 75 eraser. Because of this arrangement, very little of the eraser will be wasted, which is a common fault of most eraser holding devices attached to pencils or the like now on the market.

It will be noted from the drawings that I have illustrated but one lip. However, more lips can be formed in the eraser holder if deemed desirable. I have found upon experiment that two lips, smaller in diameter 80 than the one illustrated in the drawings, and formed opposite each other, will cause a greater amount of frictional engagement between said cap and said eraser holding 85 device.

Therefore, while I have illustrated and described the preferred form of construction for carrying my invention into effect, the structure is capable of variation and modification without departing from the spirit of 90 the invention.

Having described my invention, what I claim as new and desire to secure by Letters Patent is:—

1. An eraser holder having means for 100 gripping an eraser, and a cap adapted to enclose the end of said holder, the said means being further adapted to releasably lock said cap against longitudinal movement relative to said holder.

2. An eraser holder having resilient means for gripping an eraser, and a cap adapted to enclose the end of said holder, the said 105

means being further adapted to releasably lock said cap against longitudinal movement relative to said holder.

3. An eraser holder having movable means for gripping an eraser, and a cap adapted to enclose the end of said holder, the said means being further adapted to releasably lock said cap against longitudinal movement relative to said holder.

10 4. An eraser holder having means for re-

taining a portion of an eraser within the holder and a resilient tongue adapted to contact with the eraser, and a cap for covering the eraser, the said tongue being adapted to releasably lock said cap against longitudinal movement.

In witness whereof I have hereunto subscribed my name.

J E JOHNSON.
